ELECTRO-SURGICAL HANDLE

Eugene Olsen, Lafayette, Calif.
(3820 Broadway, Oakland, Calif. 94611)

Filed Feb. 22, 1972, Ser. No. 228,429

Term of patent 14 years

Int. Cl. D24—02

U.S. Cl. D83—12

FIG_1

FIG_2

FIG_3

FIG_5

FIG_4

FIG. 1 is a top plan view of an electro-surgical handle showing my new design;

FIG. 2 is a side elevational view thereof;

FIG. 3 is a front end view thereof;

FIG. 4 is a rear end view thereof; and

FIG. 5 is a front end view of a modified form of the handle illustrated in FIG. 3.

I claim:

The ornamental design for an electro-surgical handle, substantially as shown and described.
